(57) **CLAIM**

The ornamental design for a novel heater supported by a rotatable stand, as shown and described.

DESCRIPTION

FIG. 1 is a right front perspective view of the novel heater supported by a rotatable stand showing our new design; FIG. 2 is a left front perspective view thereof;

FIG. 3 is a right rear perspective view thereof;

FIG. 4 is a left rear perspective view thereof;

FIG. 5 is a left side view thereof;

FIG. 6 is a right side view thereof;

FIG. 7 is a front view thereof;

FIG. 8 is a rear view of thereof;

FIG. 9 is top perspective view thereof; and

FIG. 10 is bottom view thereof.

The broken-line disclosure in the views is for illustrative purposes only and forms no part of the claimed design.
